UNITED STATES PATENT OFFICE

BURT N. PIERCE, OF NEW YORK, N. Y., ASSIGNOR TO EMEROL MANUFACTURING CO., OF NEW YORK, N. Y., A CORPORATION OF ILLINOIS

LUBRICATING SYSTEM FOR INTERNAL COMBUSTION ENGINES

Application filed July 23, 1931. Serial No. 552,726.

This invention relates to certain new and useful improvements in lubricating systems for internal combustion engines and more particularly to the construction of drip spoon carried by the diaphragm whereby the oil drawn through the diaphragm by the suction of the engine will drop one drop at a time in order to allow the drops to be counted in order to record the amount of lubricant being fed to the cylinders of the engine.

The nature of this invention is a slight improvement over the drip spout disclosed in an application filed by Vernon W. Thompson and Burt N. Pierce, December 8, 1930, Serial Number 500,928.

A still further object of the invention is to provide a drip spoon which is provided with a trough portion and a tongue, the trough portion being adapted to be secured to the diaphragm by an apertured plug through which the lubricant passes into the trough portion and then from the trough portion onto the tongue portion in order to allow it to drop a drop at a time in front of the sight opening.

Other and further objects of the invention will be hereinafter set forth and the novel features thereof defined by the appended claims.

In the drawing,

Figure 1 is a vertical section showing the diaphragm drip spoon in position;

Figure 2 is a vertical section taken at right angles to that of Figure 1 showing the diaphragm and drip spoon in section with the cooperating needle valve working in the plug for holding the drip spoon in position on the diaphragm; and

Figure 3 is a detail perspective view of the drip spoon and a portion of the diaphragm and the apertured plug and nut for holding the same.

As shown in the application filed by Vernon W. Thompson and myself, Serial Number 500,928, a housing A is employed in connection with my improved construction of lubricating system having an inlet 1 and an outlet 2, said housing being provided with a flexible diaphragm 3 and a sight opening 4.

The lubricant to be supplied to the engine is

adapted to be drawn from a source of supply through inlet 1 through the diaphragm and out through the outlet 2 so as to lubricate the valves and walls of the cylinders.

In a companion application filed even date herewith, I have shown and described the particular construction of housing and the invention in this application resides in the particular construction of drip spoon.

The flexible diaphragm 3 forms two chambers in the housing, one of which is in communication with the inlet 1 and the other with the outlet 2.

The diaphragm is provided with a central opening through which is adapted to pass an apertured threaded plug 5 for securing the drip spoon in position on one face of the diaphragm, said drip spoon comprising a trough portion 6 having an aperture through which plug 5 is adapted to pass, 70 said aperture being adapted to register with the aperture in the diaphragm and said drip spoon is secured in position thereon by a nut 7 which clamps the head of the threaded plug 5 against the bottom of the trough of 75 the drip spoon as clearly shown.

The drip spoon is provided with an inclined wall 8 which terminates in a substantially downwardly and outwardly projecting V-shaped tongue 9 from which the lubricant 80 passing through the apertured plug is adapted to drop a drop at a time in front of the sight opening 4.

With this construction the drip spoon can be readily secured in position on the diaphragm and removed therefrom and by employing an apertured plug, I form a valve seat for a needle valve 10 which regulates the passage of the lubricant passing from a source of supply to the engine.

From the foregoing description it will be seen that I have provided a lubricating system for an internal combustion engine cooperating with a needle valve for regulating the supply of lubricant to the engine, said diaphragm carrying a drip spoon locked in its adjusted position by a plug and nut.

What I claim is:—

1. In a lubricating system for an internal combustion engine having a housing, a flex-

ible apertured diaphragm mounted in said housing through which lubricant is adapted to pass from the source of supply to the engine and a drip spoon disposed under the 5 aperture of said diaphragm.

2. In a lubricating system for an internal combustion engine, the combination with a housing provided with a sight opening, of a flexible diaphragm disposed in said housing 10 having an opening through which lubricant is adapted to pass from the source of supply to the engine, a plug arranged in said opening and a drip spoon secured to one face of said diaphragm by said plug.
- 15 3. In a lubricating system for internal combustion engines, a housing, a diaphragm mounted in said housing having an aperture, a drip spoon arranged over said aperture, a plug passing through said drip spoon and 20 aperture of the diaphragm for securing said spoon in position on said diaphragm, said drip spoon having a downwardly and outwardly projecting tongue.
- 25 4. In a lubricating system for internal combustion engines, the combination with a housing having a diaphragm mounted therein provided with an aperture, an apertured plug extending through the aperture of said diaphragm having a threaded portion carrying 30 a nut, an apertured drip spoon arranged on said plug against the face of said diaphragm, said drip spoon being provided with a downwardly extending substantially V-shaped tongue.
- 35 5. In a lubricating system for internal combustion engines, a housing provided with a sight opening and an inlet and outlet, a diaphragm arranged between said inlet and outlet, an apertured plug arranged in said diaphragm through which lubricant is adapted 40 to pass, a drip spoon carried by said plug having an inclined wall terminating in a downwardly projecting tongue and a valve cooperating with the plug for regulating the 45 passage of lubricant passing through said housing.

In testimony whereof I hereunto affix my signature,

BURT N. PIERCE.
